Specification of Letters Patent.

Patented Jan. 20, 1914.

Application filed February 24, 1911. Serial No. 610,512.

To all whom it may concern:

Be it known that I, LYNN A. WILLIAMS, a citizen of the United States, residing at Evanston, in the county of Cook and State 5 of Illinois, have invented a certain new and useful Improvement in Automatic Time-Accounting Devices, (Case 7².) of which the following is a full, clear, concise, and exact description, reference being had to the accompanying drawings, forming a part of this specification.

My invention relates to automatic time-accounting devices and has for its object the provision of a mechanism for automatically 15 taking account of a workman's time or wages. In devices of this kind, the arrangement is usually such that a workman's register is actuated periodically step by step, these periodic movements being controlled 20 either by a clock directly or by some clock-governed motor.

In the prior art the mechanisms that are used for periodically actuating the registers are so constructed that the actuations occur 25 either at the beginning of a periodic interval or at the end. For instance, if a register is to be actuated every fifteen minutes, there would be four actuations every hour, no matter whether the actuations occur at the beginning 30 of the quarter or at the end. Let it be supposed that the actuations take place at the beginning of the quarter hour. In this event for the hour, let us say, between seven and eight, the register would be actuated at 7.00, at 7.15, at 7.30 and at 7.45. By this arrangement it will be seen that the workman is credited with fifteen minutes in advance during every quarter of an hour. The result of this would be that should a 35 workman disconnect his register at 11.45, he would be credited with the full quarter between 11.45 and 12.00, for the reason that the register was actuated at 11.45. On the other hand, should it be desired to escape 40 this difficulty by causing the register to actuate at the end of a predetermined interval, so that the workman would be credited with a certain period only after such period had elapsed, then this difficulty arises: Let it be 45 supposed that the beginning of the day's work is at 7.00 and that the workmen's registers are actuated at the end of every fifteen minutes so that the first actuation would occur at 7.15. It is evident that the workman 50 who sets his register in operation any time before 7.15, as for instance, at 7.14, would be credited with the full fifteen minutes between 7.00 and 7.15. From these illustrations it should be plain that no matter whether a register is actuated at the beginning of a predetermined interval or at the end of such interval, it will be possible for a workman to credit himself with time and wages to which he is not entitled. Inventors along this line have recognized this difficulty 55 and there are patents in the art which show devices for causing registrations to be made at the beginning as well as at the end of periodic intervals, and subsequently making proper corrections for the over-actuations. 60 A concrete example will make clear just what is meant: Assuming that the register is to be operated once every fifteen minutes, then, according to certain of the devices in the prior art, such a register would be operated at 7.00, at 7.15, at 7.30, at 7.45 and at 8.00. There would thus be five one-quarter hour actuations for every hour. The purpose of this is, of course, to compel the workman to throw in his register at the beginning 65 of an interval, and not to throw it out before the end of the interval, if he is to be credited with that interval. By the above arrangement, if a workman were to throw his register out of operation at any time between 7.45 and 8.00, he would not be credited 70 with that interval for the reason that there was no actuation at 8.00. Obviously, the result of such an arrangement is that the workman's time and wage record at the end of 75 the day is too large. Accordingly, devices in which the actuations occur at the beginning and at the end of periodic intervals have auxiliary arrangements whereby the workman's record, at certain times, is run 80 backward a sufficient amount to make the proper corrections. This is, of course, an 85 awkward and undesirable arrangement.

The object of my present invention is a 90 register-actuating device which operates the register at the end of periodic intervals, with the provision that the workman is required to set his register-operating mechanism into actuating position at the beginning of an 95 interval. The result of this is that although there is but one actuation during an interval, yet this actuation will not occur unless the mechanism has been set into operating position at the beginning of the interval by 100 the workman. Furthermore, according to 105 110

my invention, if a workman should during an interval throw his actuating clutch into inoperative position, it will be impossible for the clutch to make operative connection 5 with the register-operating mechanism except at the beginning of the next interval. In other words, if a workman is to be credited with an interval it is necessary for him to allow his clutch to remain in operative 10 position during that entire interval. Also, according to my invention, the beginning and ending periods for which credit is given may, if desired, be different,—as explained later on. These and further objects and 15 results of my invention will become apparent as the specification proceeds.

Referring to the accompanying drawings, wherein like characters refer to corresponding parts, Figure 1 is a front view of my device. Fig. 2 is a side view partly in cross-section for the sake of clearness. Fig. 3 shows a suitable arrangement for actuating the clutch-member hereinafter referred to. Fig. 4 is a top view of Fig. 3. Fig. 5 is a 20 view on line 5—5 of Fig. 1 to show the position of certain parts when they are in operative position, as hereinafter described. Fig. 25 6 shows an arrangement of register's provided with my novel form of actuating mechanism, and a gearing arrangement whereby the actuations of several registers 30 may be totalized into a summation-register. Fig. 7 is a side view of a suitable differential gear which I may employ in connection 35 with the arrangement shown in Fig. 6; and Fig. 8 is a cross-sectional view of Fig. 7 on line 8—8.

Upon the shaft 1 is loosely mounted the ratchet-wheel 2, to which, is secured, either 40 integrally or separately, the register-actuating gear 3. For the sake of simplicity I have indicated a register diagrammatically at R, connected with the gear 3 through gear 3'. Beside the ratchet-wheel 2 is 45 mounted an arm 4, this arm being free to turn on the shaft 1. The wheels 2 and 3 and the arm 4 are prevented from longitudinal movement on the shaft by being held between two collars 5 and 6 secured to the 50 shaft. The arm 4 is, at its outer end, provided with a pawl 7 pivoted thereon at 8. As seen from Fig. 1, this pawl is adapted to engage the teeth of the ratchet-wheel 2. The arm 4 is furthermore provided with a 55 casing or housing 9 within which is secured a lug 10. This lug has an extension 11 within the housing, one end of the stem projecting through an opening in the arm 4, as may be seen from Fig. 2. A spring 12, 60 bearing at one end against the washer 13 on the stem of the lug and at its other end against the arm 4, normally tends to hold the lug outwardly in the position in which it is shown in Figs. 1, 2 and 5. This lug, if 65 desired, may have its outer edge reduced, as

shown at 14 in Fig. 5, in order to reduce the contact area between the lug and the clutch-member when the latter is thrown into operative position during an interval, as will be more fully explained. Secured to the 70 shaft 1 so as to rotate therewith is a clutch member 15. This member, which is splined upon the shaft as clearly shown in Fig. 2 so that it may be moved longitudinally thereon, may be of any convenient form. In the 75 example of my invention illustrated, I have shown this clutch-member 15 in the shape of a disk provided with the sector portion 16. Any suitable arrangement may be employed for shifting this clutch-member along 80 the shaft into operative position, that is to say, into a position in which the side 17 of the sector portion will engage with the lug 9, as shown in Fig. 5. One convenient way of accomplishing this is illustrated in the 85 drawings. A yoke 22 has the outer ends of its arms engaging in a groove 23 in the hub of the clutch-member. This yoke is pivoted at 24 and has an extension 25. A handle in the form of a loop 26 is formed on the lower 90 end of the extension to provide a handle whereby a workman may readily throw his clutch into and out of operative position. Also, in order that the clutch may not be accidentally shifted from one position to another any suitable means may be employed for retaining the clutch in its shifted position. In Fig. 2 I have shown a spring blade 27 so supported with respect to the extension 25 that the latter will rest upon one side or 95 the other of the projection or displacement 100 28 on the spring blade. This clutch-member is adapted to be moved periodically forward, in the direction indicated by the arrow in Fig. 1. This forward movement takes 105 place during a predetermined interval and at the end of the interval the clutch-member is automatically restored to its initial position, which is the position in which it is shown in Fig. 1. Various schemes may be 110 employed for producing this oscillatory movement of the clutch-member. For the sake of illustration I have shown the shaft 1 provided with an arm 18, as shown in Figs. 3 and 4. This arm is rigidly secured to the 115 shaft and is, at its outer end, provided with the extension 19. A cam 20 is associated with the arm 18 so that the extension 19 will ride over the surface of the cam as the latter 120 is rotated. The movement of the cam is 125 controlled by a clock in any suitable manner.

In order to best explain the operation of my device, I shall assume, for the sake of illustration, that the cam 20 makes one revolution every fifteen minutes in the direction indicated by the arrow in Fig. 3. At the beginning of an interval the extension 19 on the arm 18 will rest in the lowermost position 21 of the cam surface, as indicated in 130

dotted lines in Fig. 3. At this moment the angular position of the clutch-member 15 will be that indicated in Fig. 1. From this position of the clutch-member it will be seen that one side of the lug 10 and the engaging portion 17 of the clutch-member are substantially in alinement, so that should the clutch-member be moved toward the arm 4, the lug 10 and the clutch-member will engage each other, as shown in Fig. 5, whereby the arm 4 and the clutch-member will be virtually locked together. Therefore, as the arm 18 is raised by the movement of the cam, the clutch-member will carry with it the arm 4. The parts are so proportioned that when at the end of an interval the arm 18 is at the highest point of the cam surface and is ready to drop into its initial position, the angular movement of the clutch-member and the arm 4 will be precisely the distance of one tooth on the ratchet-wheel 2. The result is that at the end of the interval the pawl 7 on the arm 4 will drop into the next succeeding tooth on the ratchet-wheel. The moment that the arm 18 drops back into its initial position, the clutch-member 15 will, of course, be likewise moved back into its initial position, that is to say, into the position in which it is shown in Fig. 1. During this forward movement of the clutch-member and the arm 4, while the pawl 7 is riding up the inclined surface of the engaging tooth, accidental rotation of the ratchet-wheel in that direction is prevented by the locking dog 7', which is held against the teeth of the ratchet-wheel by the spring 8'. As soon as the locking engagement between the lug 10 on the arm 4 and the clutch-member is broken, the spring 29 secured to the outer end of the arm 4 asserts itself and draws the arm 4 back into its initial or inoperative position. A stop 8", or any suitable means, limits the return movement of the arm. This return or backward movement of the arm is accompanied by a movement of the ratchet-wheel whereby the register R (see Fig. 2) is operated through the gears 3 and 3'. Inasmuch as the angular position of the clutch-member begins to change from the very beginning of an interval and continues to change to the end of the interval, it will be apparent that at any time during an interval, the position of the clutch-member, assuming it to be in its inoperative position as shown in Fig. 2, will be such that the engaging portion 17 will have traveled past the lug 10. So that, should the workman throw his clutch-member into operative position during an interval, the sector portion 16 will abut against the end of the lug 10, forcing the latter into its housing 9. It will be seen that in this way there is no locking engagement effected between the arm 4 and the clutch-member. The latter will simply move by the inwardly pressed lug without

producing any movement of the arm 4. At the end of the interval the clutch-member will be restored to the position in which it is shown in Fig. 1, and there will have been no actuation of the register at that moment. Should the workman leave his clutch in, then at the beginning of the new interval, the lug 10 will be freed and permitted to extend so as to be engaged by the clutch-member 15, as shown in Fig. 5. With the parts thus locked together at the beginning of the interval, the register will be actuated at the end of the interval, as above explained. Suppose, now, a workman should throw his clutch out toward the close of an interval. The result of this would be that the arm 4 would be drawn back into its initial or inoperative position without actuating the ratchet-wheel 2, for the reason that the pawl 7 would not have dropped onto the next tooth, this action of the pawl 7 not occurring before the end of an interval. The workman would, therefore, receive no credit for the interval during which he threw his clutch into inoperative position. It should be apparent from this description of the operation of my device that it is necessary for a workman to throw his clutch into operative position at the beginning of an interval in order to receive credit for that interval, with the further provision that he must not throw his clutch out before the end of the interval. In this way a workman is compelled to be present during the entire period for which he is to be credited in time and wages. Also, no corrections of any kind need be necessary as in the devices of the prior art, for the reason that the register-operating device herein shown actuates the register only the proper number of times during any given period. That is to say, if the register is to be actuated every quarter of an hour, there will be only four actuations during that hour, one at the end of every quarter.

Various other results and effects may be accomplished by my invention. For instance, by causing the forward swing of the clutch-member to equal the space of more than one tooth it is possible to make a beginning period different from an ending period. This may be best explained by assuming a concrete illustration. Let it be supposed that the clutch-member moves forwardly during every half hour the distance of two teeth. In this way the beginning period is equal to half an hour, whereas the ending period will amount to fifteen minutes only. That is to say, a workman who has not started by seven in the morning will receive no credit until 7.30 and thereafter. If, however, he works until 11.46, he will get credit for the fifteen minutes between 11.30 and 11.45, because when he throws his clutch out of operative position

at 11:46, the pawl 7 of the arm 4 will have dropped into the next succeeding tooth, whereby, when the arm is released, it will be drawn back by the spring 29 the distance of one tooth. In this way the register would be actuated to give the workman credit for the fifteen minute interval just mentioned.

In Fig. 6 I have shown an arrangement whereby the actuations of several registers 10 may be totalized into one or more summation-registers. Inasmuch as the different parts of the register-operating device shown in Fig. 6 are the same as those shown in the other figures, and already described above, 15 I shall simply refer to the gearing arrangement in this figure. The gear 3 of each register-operating mechanism engages with a gear 32, which gear in turn engages with a gear 33 for driving the associated register. 20 The gear 32 is connected to one end of a sleeve 34 loosely mounted on the shaft 35. The other end of the sleeve 34 has secured thereto one member 36 of a differential gear indicated as a whole by 37. As shown in 25 the detail views of Figs. 7 and 8, the central member 38 of this differential set has journaled therein two pairs of pinions 39, 40 and 41, 42, respectively. The shaft 43 of each pinion is at its end journaled in the 30 housings 44 and secured to the central gear 38. The pinions 39 and 40 constituting one pair are in mesh with each other, and the pinions 41 and 42 constituting the second pair are in mesh with each other. Although 35 I have shown two pairs of these pinions, it is clear that one pair only might be used. The pinions 39 and 41 are in engagement with the teeth of the gear wheel 36, while the pinions 40 and 42 are in mesh with the teeth 40 of the gear wheel 36'. The proportions of the various parts of this differential gear mechanism are such that the rotations of the gear wheels 36 and 36' will be added by the central member 38 and transferred into 45 the gear 44 of the summation-register AB. The actuations of registers A and B will, therefore, be totalized in the summation-register AB. Similarly, will the actuations of registers L and M be totalized into the 50 summation-register LM. Should further totalization be desired, the differential gear connection above described may be extended to the summation-registers AB and LM so as to totalize the actuations of these two 55 registers into a final summation-register. Various other arrangements of the registers will suggest themselves to those skilled in the art.

Although I have shown a specific structure to illustrate my invention, I would have it understood that such illustration is merely by way of example, and that various alterations and modifications may be made in many of the details to carry out the essence 60 of my invention. Thus, for instance, the

clutch-member may be of any suitable form other than that shown in the drawings. So also may the part designated by 3 and herein called an arm take the form of, for instance, a disk. Also, the differential gearing herein shown may be substituted by any other desirable form. 70

Having thus described my invention, what I desire to claim as new and secure by Letters Patent of the United States is:

1. In combination, a time-controlled shaft, an arm loosely mounted thereon and provided with a pawl, a ratchet-wheel adapted to be actuated by said pawl, a clutch-member secured to said shaft to rotate therewith, means on said arm extending into the path of rotation of said clutch-member, whereby the movement of the latter in one direction is accompanied by a corresponding movement of said arm without actuating said ratchet-wheel, means for moving said arm in the reverse direction to actuate said ratchet-wheel, and a register adapted to be operated by said ratchet-wheel. 80

2. In combination, a time-controlled shaft, 90 an arm loosely mounted thereon and provided with a pawl, a ratchet-wheel adapted to be actuated by said pawl, a clutch-member secured to said shaft to rotate therewith, means for temporarily locking said arm and 95 clutch-member together, whereby the movement of the latter in one direction is accompanied by a corresponding movement of said arm without actuating said ratchet-wheel, means for moving said arm in the reverse direction to actuate said ratchet-wheel, and a register adapted to be operated by 100 said ratchet-wheel.

3. In combination, a time-controlled shaft, 105 an arm loosely mounted thereon and provided with a pawl, a ratchet-wheel adapted to be actuated by said pawl, a clutch-member secured to said shaft to rotate therewith, but 110 slideable longitudinally thereon, means for shifting said clutch-member into operative and inoperative position, a lug on said arm 115 extending into the path of rotation of said clutch-member when the latter is in its operative position, whereby the movement of said clutch-member in one direction is accompanied by a corresponding movement of 120 said arm without actuating said ratchet-wheel, means for moving said arm in the reverse direction to actuate said ratchet-wheel, and a register adapted to be operated by 125 said ratchet-wheel.

4. In combination, a movable arm provided with a pawl, a register, mechanism adapted to be actuated by said pawl for operating the register, a clutch-member adapted to be periodically actuated in alternate directions, means for temporarily locking said arm and clutch-member together, whereby the movement of the latter in one direction is accompanied by a corresponding 130

- movement of said arm without actuating said register-operating mechanism, a cam for operating said clutch member, and means for moving said arm in the reverse direction to actuate said mechanism, whereby the register is operated.
5. In combination, a shaft, a movable member loosely mounted thereon, a register, mechanism controlled by said movable member to operate the register at predetermined intervals, a second member secured to said shaft to rotate therewith, means for periodically actuating said shaft in alternate directions, means for locking said members together during movement of said shaft in one direction without affecting said register-operating mechanism, said second member being free from the movable member during the reverse movement of the shaft, and means for moving said first-mentioned member in the reverse direction to actuate said mechanism, whereby the register is operated.
6. In combination, a register, a first member for operating the same, an oscillating time-controlled member adapted to be periodically actuated in the same direction during predetermined intervals during both operative and inoperative positions of said time-controlled member relatively to said first member, means for moving said time controlled member into and out of operative position with respect to said first member, means for permitting connection between said time controlled member and first member only at the beginning of an interval when said time controlled member is moved into operative position, and means whereby, with such connection established, said first member is actuated at the end of the interval to operate the register.
7. In a register-operating device, the combination of mechanism for actuating the register, a time-controlled clutch-member adapted to be actuated during periodic intervals, means for permitting locking engagement between said mechanism and said clutch-member only at the beginning of an interval to cause actuation of the register at the end of the interval, and a cam for operating the clutch member.
8. In a register-operating device, the combination of a movable arm provided with a pawl, register-operating mechanism adapted to be actuated by said pawl upon movement of said arm in the proper direction, a time-controlled clutch-member adapted to be actuated during periodic intervals, means for permitting locking engagement between said mechanism and said clutch-member only at the beginning of an interval, and means for moving said arm at the end of an interval to actuate said mechanism.
9. In a register-actuating device, the combination of a movable arm having a lug, a clutch-member associated with said arm and provided with an engaging portion, means for rotating said member forwardly during periodic intervals and automatically restoring it to its initial position at the end of an interval, and means for shifting said member into operative position, said engaging portion and said lug being arranged to permit a connection between said arm and said clutch-member at the beginning of an interval, when said clutch-member is shifted to its operative position, but to prevent the establishing of such connection during an interval.
10. In a register-actuating device, the combination of a movable member having a pawl, a register, mechanism adapted to be actuated by said pawl for operating the register, a lug on said arm, a clutch-member associated with said arm and provided with an engaging portion, means for rotating said member forwardly during periodic intervals and automatically restoring it to its initial position at the end of an interval, means for shifting said member into operative position, said engaging portion and said lug being arranged to permit a connection to be made between said arm and said clutch-member only at the beginning of an interval when said member is shifted to its operative position, whereby said members are moved forwardly together during the interval, and means for moving said arm in the reverse direction at the end of an interval to actuate the register.
11. The combination of a register, a first member for periodically actuating the same at the end of predetermined intervals, a clutch-member associated with said first member, and means requiring a connection between said first member and said clutch-member to be made at the beginning of an interval in order to cause actuation of the register at the end of the interval.
12. The combination of a register, a first member for periodically actuating the same at the end of predetermined intervals, a clutch-member associated with said first member, and means for compelling continuous connection between said first member and said clutch-member from the beginning to the end of an interval, in order to cause said first member to actuate the register at the end of the interval.
13. A register-actuating device comprising, in combination, a movable arm held normally in an inoperative position, a ratchet-wheel adapted to be actuated thereby, a clutch-member arranged for periodic connection with said arm during predetermined intervals to move the same into operative position, and means for automatically restoring said arm to its initial position without actuation of said ratchet-wheel, should the clutch-member be thrown out of

engagement with said arm before the end of an interval.

14. A register-actuating device comprising, in combination, a movable arm held normally in an inoperative position, a ratchet-wheel adapted to be actuated thereby, a clutch-member arranged for periodic connection with said arm during predetermined intervals to move the same into operative position, and means for compelling continuous connection between said arm and said clutch-member from the beginning to the end of an interval, in order to cause said arm to actuate said ratchet-wheel at the end of the interval.

15. In combination, a shaft, a plurality of clutch-members slidably secured thereon, means for periodically actuating said shaft forwardly during predetermined intervals, mechanism associated with each clutch-member, a register adapted to be operated by said mechanism, and means requiring a connection between each mechanism and its corresponding clutch-member to be made at the beginning of an interval in order to cause actuation of the associated register at the end of the interval.

16. In combination, a shaft, a plurality of clutch-members slidably secured thereon, means for periodically actuating said shaft forwardly during predetermined intervals, mechanism associated with each clutch-member, a register adapted to be operated by said mechanism, means requiring a connection between each mechanism and its corresponding clutch-member to be made at the beginning of an interval in order to cause actuation of the associated register at the end of the interval, and means for totalizing the actuations of two or more of said registers.

17. In combination, a shaft, a plurality of clutch-members slidably secured thereon, means for periodically actuating said shaft forwardly during predetermined intervals, mechanism associated with each clutch-member, a register adapted to be operated by said mechanism, means requiring a connection between each mechanism and its corresponding clutch-member to be made at the beginning of an interval in order to cause actuation of the associated register at the end of the interval, a summation-register, and differential gearing between two or more of said first-mentioned registers and said summation-register, for totalizing the actuations of said first-mentioned registers into said summation-register.

18. In combination, a shaft, a plurality of clutch-members slidably secured thereon, means for periodically actuating said shaft forwardly during predetermined intervals, mechanism associated with each clutch-member, a register adapted to be operated by said mechanism, and means for compelling

continuous connection between any mechanism and its corresponding clutch-member from the beginning to the end of an interval, in order to cause said mechanism to actuate the associated register at the end of the interval.

19. In combination, a shaft, a plurality of clutch-members slidably secured thereon, means for periodically actuating said shaft forwardly during predetermined intervals, mechanism associated with each clutch-member, a register adapted to be operated by said mechanism, means for compelling continuous connection between any mechanism and its corresponding clutch-member from the beginning to the end of an interval, in order to cause said mechanism to actuate the associated register at the end of the interval, and means for totalizing the actuations of two or more of said registers.

20. In combination, a shaft, a plurality of clutch-members slidably secured thereon, means for periodically actuating said shaft forwardly during predetermined intervals, mechanism associated with each clutch-member, a register adapted to be operated by said mechanism, means for compelling continuous connection between any mechanism and its corresponding clutch-member from the beginning to the end of an interval, in order to cause said mechanism to actuate the associated register at the end of the interval, a summation-register, and differential gearing between two or more of said first-mentioned registers and said summation-register, for totalizing the actuations of said first-mentioned registers into said summation-register.

21. In a register-operating device, the combination of a first member for actuating the register, a clutch-member, time controlled means for actuating the same during periodic intervals and means for permitting locking engagement between said first member and said clutch-member only at the beginning of an interval to cause actuation of the register at the end of the interval to give credit for that interval, said time controlled means being adjustable to vary the actuations of said clutch-member, whereby the beginning and ending periods for which credit is given may be different.

22. In combination, a plurality of registers, mechanism for determining time intervals, devices actuating during such interval to store register operation corresponding thereto, means for communicating such stored operation to a desired one of the registers at the end of each interval, and means for integrating the operation of such registers.

23. In combination, a plurality of registers, mechanism for determining time intervals, devices actuating during such interval to store register operation corresponding

thereto, means for communicating such stored operation to a desired one of the registers at the end of each interval, means for integrating the operation of such registers, and means for interrupting the storing operation during such interval and thereby preventing the operation of the corresponding register.

24. In combination, a register, devices for storing register operation during each of successive time intervals, means for communicating such stored operation to the register at the end of such intervals, and means for interrupting the storing operation during one interval to prevent registration until the end of the next interval.

25. In combination, a register, operation storing devices adapted to cyclic operation, means for effecting connection between the storing devices and the register at but one point in the cycle, and a member for driving the storing devices, such member adapted to be brought into driving relation at a second point only in each cycle.

26. In combination, a register, operation storing devices adapted to cyclic operation, means for effecting connection between the storing devices and the register at but one point in the cycle, and a member for driving the storing devices, such member adapted to be brought into driving relation at an opposite point only in such cycle.

27. In combination, a first member having periodic motion, a register, a second

member for actuating the register a definite amount for each period of motion of said first member, and devices for establishing operative connection at will between said members.

28. In combination, a first member having periodic motion, a register, a second member for actuating the register a definite amount for each period of motion of said first member, and devices for establishing operative connection at will between said members, interruption of said operative connection during any period preventing actuation of the register for that period.

29. In combination, a first member having periodic motion, a register, a second member for actuating the register a definite amount for each period of motion of said first member, and devices for establishing operative connection at will between said members, actuation of said devices for establishing said operative connection during one of said periods serving to establish said operative connection at the beginning of the next succeeding period to operate said register at the end of said next succeeding period.

In witness whereof, I hereunto subscribe my name this 20th day of February, 1911.

LYNN A. WILLIAMS.

Witnesses:

RAGNA C. THORESON,
LEONARD W. NOVANDER.
